UNITED STATES PATENT OFFICE.

JOHN Q. C. SEARLE, OF CINCINNATI, OHIO.

IMPROVEMENT IN FURNACES FOR STEAM-BOILERS.

Specification forming part of Letters Patent No. 175,510, dated March 28, 1876; application filed March 17, 1876.

To all whom it may concern:

Be it known that I, JOHN Q. C. SEARLE, of Cincinnati, Hamilton county, State of Ohio, have invented certain Improvements in Steam-Boilers, of which the following is a specification:

The main object of my invention is the effectual and economical consumption of fuel in steam-boilers—an object which I attain by so combining a partition in the fire-place with a depression in the grate that the products of combustion must, before reaching the flues of the boiler, pass through a mass of incandescent fuel lodged in the said depression, as explained hereafter.

The accompanying drawing illustrates my invention as applied to a boiler of the locomotive type.

Figure 1 is a vertical section of the fire-box end of the boiler with my improvements; Fig. 2, a transverse vertical section on the line 1 2; and Figs. 3 and 4, detached views, illustrating parts of my invention.

A is the outer shell of the body of the boiler; B the fire-box; E, the tube-sheet, and F the grate. On the opposite sides of the fire-box, at a short distance from the tube-sheet, are arranged hollow projecting ribs a a', the interior of each rib being in free communication with the adjoining water-space. Each hollow projection has flanges b b for supporting the removable water-back G, and is connected to the same by pipes H, which are so bent or otherwise arranged that the said water-back can expand and contract without any deteriorating effect on the joints of the pipes. As a further means of securing the water-back to its place I employ studs e, which screw into the outer shell of the boiler and pass through tubular stays f, the point of each screw fitting into a recess in the edge of the water-back. The two feed-pipes J J pass through thimbles f in the water-leg K, and are connected to the water-back at or near the lower portion of the same, the feed-water being thus forced directly into the said water-back, whence it passes through the pipes H H into the water-spaces of the fire-box. When the water-back has to be removed for the purpose of gaining access to the flues all that is necessary is to uncouple the feed-pipes J and

circulating-pipes H, and withdraw the screw-studs e, when the said water-back can be removed from its bearings on the flanges b. A partition of fire-clay or other refractory material, of the same shape and occupying the same position as the water-back, may be substituted for the latter, which, however, I prefer in all cases. The upper portion of the partition consists of a damper, L, and plate d, the damper being so hinged to the fire-box that it can be moved outward to the position shown by dotted lines, when it is desirable for a portion of the products of combustion to pass over the water-back. The grate F is continued in a horizontal position to the point x, where it meets the inclined or curved grate F¹, and to the lower end of the latter is hinged the tilting grate F², these two grates constituting the depression through which, and through the fuel lodged therein, the products of combustion must pass before they reach the flues of the boiler. As the air has free access through the grate F¹ and F² to the depressed mass of fuel the latter must burn fiercely, and the products of the combustion of the fuel on the grate F must, on passing through the depressed fuel, be thoroughly ignited and pass in the form of a flame of intense heat through the throat N, between the inclined top p of the water-leg K and the lower edge of the water-back.

In locomotive-boilers it is essential to promote the combustion of the depressed fuel by a forced blast, which I prefer to produce by means of steam-jets, in the manner shown in the drawing, where M represents a pipe to which air has free access, and which has nozzles w directed toward the grate F¹ and to the entrance of the throat N. A steam-pipe, m, communicating with the steam-space of the boiler, is contained within the air-pipe M, and is so perforated that a jet of steam is projected into each nozzle w, from which air and steam combined are consequently projected through the grate F¹. I also prefer in the case of locomotive-boilers to force air through the grate F at the front of the same, for which purpose I arrange beneath the grate two inclined plates, t t, converging toward the top, where there is a narrow opening, a perforated steam-pipe, q, being contained between the

plates, so that jets of steam will be projected upward and induce a forcible volume of air to pass through the grate, and this air will have a tendency to ignite the gases emanating from the fuel at the front of the furnace.

The inclined plates *t t* possess this advantage, that they are self-cleaning, for no ashes or other refuse can be lodged on them.

I claim as my invention—

1. The combination, in a steam-boiler furnace, of a depressed grate at the rear of the fire-box or fuel-chamber, the front of which depressed grate is open, with a partition, by which the products of combustion are compelled to pass through the fuel on said grate, substantially as set forth.

2. The combination of the depressed grate, the partition above the same, and the throat *N* with devices for forcing air into the fuel contained on the said depressed grate and toward the throat *N*, as specified.

3. The removable water-back *G*, adapted to the fire-box, in combination with feed-pipes *J J* and circulating-pipes *H H*.

In testimony whereof I have signed my name to this specification in the presence of two subscribing witnesses.

JOHN Q. C. SEARLE.
